GERMICIDAL DETERGENT COMPOSITIONS

John L. Darragh, Alamo, and Gordon B. Johnson, Berkeley, Calif., assignors to California Research Corporation, San Francisco, Calif., a corporation of Delaware

No Drawing. Application June 26, 1952,
Serial No. 295,808

16 Claims. (Cl. 252—106)

This invention relates to a novel germicidal detergent composition. More particularly, the invention is concerned with a germicidal detergent composition comprising an organic anionic detergent and a quaternary ammonium germicide in chemical complex with a halogen. 15

Anionic surface-active agents are commonly employed in detergent compositions. Although they are excellent cleansing agents, they have very little germicidal activity.

Quaternary ammonium germicides are also well known. They have been increasingly employed as disinfectants for the sanitization of equipment in various industries such as the dairy industry, the food industry, laundries, etc. Although classified as surface-active agents, they are generally ineffective as detergents.

It has not been possible to mix anionic surface-active agents with quaternary ammonium germicides to obtain germicidal detergent compositions because the two reagents are not compatible. The cationic quaternary ammonium germicide in such a mixture reacts with the anionic surface-active agent with a resultant reduction in the germicidal activity of the quaternary ammonium germicide and a reduction in the detergency of the anionic.

Halogens such as iodine, chlorine and bromine are also recognized as germicides or disinfectants. Their applications are limited because of their toxic vapors and tendency to stain skin and textiles. They are also highly corrosive to equipment and irritating to human tissue when employed in germicidal portions. When the halogens are combined with anionic detergents in an effort to prepare germicidal detergent compositions, the aforementioned undesirable features are carried over unabated rendering the compositions unsuitable for general use.

It has now been found that a very effective germicidal detergent composition may be prepared comprising as its active ingredient a major proportion of an organic anionic detergent of the group consisting of alkali metal and alkaline earth metal salts of an organic sulfuric reaction product having in its molecular structure a higher alkyl radical of from 8 to 18 carbon atoms and a radical selected from the group consisting of sulfonic acid and sulfuric acid ester radicals and a minor proportion of a quaternary ammonium salt-halogen complex containing from about 0.01 to about 1.0 mols of physically-bound elemental halogen per mol of quaternary as determinable by thiosulfate titration, the cation radical of said quaternary ammonium salt being characterized by a molecular weight of at least 165 and said complex being substantially free of unbound halogen as demonstrated by a negative response to the starch-iodide paper test and, in the case of iodine, by a negative response to the starch test. Preparation of suitable starch solution for such a test is noted at pages 70 and 71 of the book "A System of Chemical Analysis for the Common Elements" by Mr. E. H. Swift, published 1939 by Prentice-Hall, Inc. The absence of unbound halogen in the complex is demonstrated also by its failure to form halogen amines when exposed to ammonia vapors.

The germicidal detergent composition as described above

2

is stable under normal conditions of use whether in dry or liquid form. No turbidity, precipitation or other indication of incompatibility of the organic anionic detergent and the cationic quaternary ammonium germicide is to be found in solutions containing the composition. 5

The compositions are excellent detergents and germicides. In normal use the compositions release no toxic vapors, nor do they cause permanent staining of skin and textiles.

10 The organic anionic detergent of the composition according to this invention may be any of the well-recognized synthetic detergents of the sulfate and sulfonate types, as will be apparent from the many illustrations hereinafter disclosed. In the above concise description of the invention it has been termed the salt of an "organic sulfuric reaction product." This latter expression is intended to signify that it includes the water-soluble alkali metal and alkaline earth salts of sulfuric esters, alkane sulfonic acids and alkyl aromatic sulfonic acids derived by the reaction 20 of sulfuric acid, oleum or fuming sulfuric acid, sulfur trioxide, chlorosulfonic acid, sulfur trioxide complexes with pyridine of ethers, acetyl sulfuric acid, sulfonyl chloride, etc. with a high molecular weight organic compound characterized by a hydrophobic group such as the higher aliphatic alcohols, fatty acid monoglycerides, alkyl aromatic hydrocarbons, and the like, having an alkyl radical of from 8 to 18 carbon atoms.

25 The quaternary ammonium salt-halogen complex in the composition of this invention may be any of the well-known class of quaternary ammonium germicides to which a halogen such as iodine, bromine, or chlorine, or mixtures thereof, has been added to give a product containing an appreciable quantity of physically-bound elemental halogen as determinable by thiosulfate titration and which 30 are substantially free of unbound elemental halogen as indicated, for example, by their failure to form halogen amines when contacted with ammonia vapors. These complexes are fully described in the copending U. S. patent application Serial No. 254,815 of John L. Darragh and Ralph House, now U. S. Patent No. 2,679,533 issued May 25, 1954. The quaternary ammonium salt-halogen complexes are conveniently prepared by adding a halogen, such as iodine, in elemental form or in the form of an aqueous or alcoholic solution of tri-iodide to an aqueous 35 solution of a quaternary ammonium germicide. Upon mixing, the halogen is taken up by the quaternary and held in a loosely-bound elemental form, whereby it is immobilized in a physical sense of the word. The halogen may be added in any amounts up to the point where 40 the quaternary ammonium salt is incapable of taking up additional halogen, as indicated by an appreciable halogen partial pressure, odor, discoloration of starch-iodide paper exposed to its vapors, or the formation of halogen amines when the addition product is tested with ammonia vapors. 45

50 In the case of iodine, which is a preferred halogen, a starch color test may be employed to detect the presence of unbound iodine.

55 The quaternary ammonium salt may be any of the well-known class of quaternary ammonium germicides characterized by the formula:

60 65 wherein at least one of the radicals R₁, R₂, R₃ and R₄ is a hydrophobic, aliphatic, aryl aliphatic, or aliphatic aryl radical of from 6 to 26 carbon atoms and the entire cation portion of the molecule has a molecular weight of at least 165. The hydrophobic radicals may be long-chain alkyl, long-chain alkoxy aryl, long-chain alkyl aryl, halogen-substituted long-chain alkyl aryl, long-chain alkyl

phenoxy alkyl, aryl alkyl, etc. in nature. The remaining radicals on the nitrogen atom other than the hydrophobic radicals are substituents of hydrocarbon structure usually containing a total of no more than 12 carbon atoms. The radical X in the above formula is any salt-forming anionic radical.

Suitable quaternary ammonium salts within the above description include the alkyl ammonium halides such as cetyl trimethyl ammonium bromide, alkyl aryl ammonium halides such as octadecyl dimethyl benzyl ammonium bromide, N-alkyl pyridinium halides such as N-cetyl pyridinium bromide, and the like. Other suitable types of quaternary ammonium salts include those in which the molecule contains ether, amide or ester linkages such as octyl phenoxy ethoxy ethyl dimethyl benzyl ammonium chloride, N-(laurylcolaminoformylmethyl)-pyridinium chloride, etc. Other very effective types of quaternary ammonium germicides are those in which the hydrophobic radical is characterized by a substituted aromatic nucleus as in the case of lauryloxyphenyltrimethyl ammonium chloride, cetylaminophenyltrimethyl ammonium methosulfate, dodecylphenyltrimethyl ammonium methosulfate, dodecylbenzyltrimethyl ammonium chloride, chlorinated dodecylbenzyltrimethyl ammonium chloride, and the like.

Preferred quaternary ammonium germicides of the above general types are the long-chain alkyl dimethylbenzyl quaternary ammonium salts, the alkyl phenoxy alkoxy alkyl dimethyl benzyl quaternary ammonium salts, the N-(acylcolaminoformylmethyl)-pyridinium halides, the long-chain alkyl trimethyl ammonium halides, the long-chain alkyl benzyl trimethyl ammonium halides, the long-chain alkyl benzyl dimethyl benzyl ammonium halides, and the long-chain alkyl benzyl diethyl ethanol ammonium halides in which the alkyl radical contains from 8-18 carbon atoms.

As mentioned before, the halogen portion of the complex of this invention may be either iodine, bromine or chlorine, or mixtures thereof, with iodine being preferred. It may be added in various proportions to the quaternary ammonium germicides described above so long as excessive amounts in the form of free unbound halides in the final product are avoided. Although the amount of halogen that will combine with the particular quaternary ammonium germicide may vary according to the molecular weight of the quaternary, usually from about 0.01 to about 1.0 mols of halogen per mol of quaternary or, more desirably, from about 0.1 to about 0.7 mols of halogen per mol of quaternary are preferred.

The chemical complexing of the halogens and the quaternary ammonium germicides is conveniently carried out at ordinary room temperatures of about 70° F. In order to facilitate the reaction it is sometimes desirable to warm the reaction mixture slightly, e. g., to from about 100° F. to about 150° F.

The organic anionic detergent of the composition of this invention may, as already mentioned, be any water-soluble alkali metal or alkaline earth salt of an organic sulfuric reaction product having in its molecular structure a higher molecular alkyl group of from 8-18 carbon atoms and a radical selected from the group consisting of sulfonic acid and sulfuric acid ester radicals. Specific examples of the salts include the sodium alkyl sulfates obtained from mixed higher alcohols produced by the reduction of coconut oil, palm kernel oil and other tropical nut oils, as well as the higher alcohols derived from sperm oil. Sodium salts of the sulfuric acid esters of higher fatty acid monoglycerides such as coconut oil fatty acid monoester of 1,2-dihydroxy propane-3 sulfuric acid ester and of sulfated higher fatty acid alkylol amides such as coconut oil fatty acid ethanol amide, are also suitable. Sodium salts of sulfated high molecular weight unsaturated organic acids and esters thereof, such as sulfated oleic acid and sulfated butyl oleate may also be employed. Also suitable are the water-soluble alkaline earth and alkali metal salts of sulfated high molecular

weight olefins obtained by dehydration of fatty alcohols or decarboxylation of unsaturated fatty acids, such as oleic acid. Sodium salts of the sulfated ethers prepared from ethylene or propylene oxide and alkylated phenols or naphthols, such as the sodium salt of para-octyl phenoxy ethoxy ethyl sulfuric acid ester are also suitable for use in the composition according to this invention.

Illustrative detergents of the sulfonate variety include the sodium salts of normal fatty alkane sulfonic acids prepared by sulfonation of kerosene and white oil fractions of paraffin-base petroleums by the action of strong sulfonating agents such as sulfur trioxide or sulfuryl chloride. Alkali metal and alkaline earth salts of higher mono-fatty acid esters of 1,2-dihydroxypropane-3-sulfonic acid such as the sodium salt of coconut oil fatty acid mono-ester of 1,2-dihydroxypropane-3-sulfonic acid may be employed. Also illustrative of suitable sulfonates for use in the composition of this invention are the salts of higher fatty acid mono-esters of the lower molecular weight hydroxyalkyl sulfonic acids as, for example, the sodium salt of the oleic acid ester of isothionic acid and of higher acid amides of low molecular amino alkyl sulfonic acids such as the sodium salt of maleic acid amide of N-methyl taurine. Alkaline earth and alkali metal salts of the higher molecular weight alcohol esters of low molecular sulfocarboxylic acids such as the sodium salt of lauryl alcohol ester of sulfo-acetic acid may be employed as well as the alcohol esters of sulfo-dicarboxylic acids such as the sodium salt of di-octylsulfosuccinic acid which are also suitable for employment in the present composition. Water-soluble salts of the higher alkylated benzene sulfonic acids such as the sodium and potassium salts of dodecyl benzene and Keryl benzene sulfonic acids may also be employed as may the water-soluble alkaline earth and alkali metal salts of ethers of high molecular weight alcohols and low molecular hydroxysulfonic acids such as the sodium salt of mono-lauryl ether of 1,2-dihydroxypropane-3-sulfonic acid.

In addition to the organic anionic detergent, the composition of this invention may also contain foam stabilizers of the type illustrated by lauric isopropanol amide.

The relative amounts of the organic anionic detergent and the quaternary ammonium salt-halogen complex may vary over a considerable range. Ordinarily, it is desirable that sufficient anionic detergent be employed to impart definite detergent properties to the composition when it is added to water for use. Sufficient quaternary ammonium germicide-halogen complex product should be employed to give the desired amount of germicidal activity to the aqueous solutions in which the compositions are used.

Usually from about 70 to 99.5 parts by weight of the organic anionic detergent and about 0.5 to 30 parts by weight of the quaternary ammonium germicide-halogen complex will be found satisfactory. More preferably the germicidal detergent compositions should contain from about 95 to 99 parts by weight of the organic anionic detergent and from about 1 to about 5 parts by weight of the quaternary ammonium germicide-halogen complex. When a foam stabilizer of the type mentioned above is employed to improve the sudsing properties of the foregoing compositions, usually from about 0.1 to 50, and more preferably from about 10 to 30, parts by weight of the foam stabilizer based on 100 parts by weight of the combined anionic detergent and quaternary-halogen complex should be used.

As already mentioned, the quaternary ammonium germicide-halogen complex product ordinarily contains from about 0.01 to about 1.0 mols of halogen per mol of quaternary ammonium germicide, and more desirably from about 0.1 to about 0.7. On a per cent by weight basis, the quaternary ammonium germicide-halogen complex should contain from about 5 to about 25% by weight of halogen in physically-bound elemental form based on the quaternary, and preferably from about 10 to 20% by weight.

A summary of various illustrative quaternary ammonium germicide-halogen complex products suitable for use in the germicidal detergent composition according to the invention is presented in the following table.

TABLE I

Immobilization of iodine as tested with starch as an external indicator

Compound	Iodine Take-up Before Yielding Starch Test	
	Gms. I ₂ per gm. Compound	Mols I ₂ per mol Compound
Dodecyl benzyl trimethyl ammonium chloride	0.40-0.47	0.6-0.7
Dodecyl benzyl dimethyl benzyl ammonium chloride	0.393	0.65
Cetyl pyridinium bromide (crystalline)	0.09	0.14
di-(dodecyl benzyl)-dimethyl ammonium chloride	0.24-0.25	0.58-0.61
di-n-octylbenzyl-di-methylammonium chloride	0.27	0.52
Dodecylphenyl trimethylammonium methosulfate	0.29	0.49
Tribenzyl methylammonium methosulfate	0.25	0.40
Dodecylbenzyltriethanolammonium chloride	0.044-0.048	0.079-0.084
p-tertiary octyl phenoxy ethoxy ethyl di-methyl benzyl ammonium chloride	0.32-0.38	0.58-0.68
Octadecyl dimethyl benzyl ammonium bromide	0.42	0.59
Tetramethyl ammonium chloride	Nil	Nil
Trimethyl phenyl ammonium chloride	Nil	Nil
Nitrobenzyltrimethyl ammonium chloride	Nil	Nil
n-octylbenzyl thiuronium chloride	Nil	Nil

It will be noted from the results tabulated above that it is the quaternary ammonium salts of a high molecular weight, usually having a molecular weight of at least 165 in the cation radical, which are preferred for taking up the halogen. These high molecular weight quaternary ammonium salts are generally referred to as "quaternary ammonium germicides" and it is in that sense that the term has been employed in discussing the quaternary ammonium germicide-halogen complex products of the present composition.

The germicidal detergent composition of the present invention may be prepared in either dry or liquid form. Aqueous slurries of the compositions are adaptable to various conventional methods of drying, such as drum drying, spray drying, and the like. In its liquid form the germicidal detergent composition of the invention may contain water and various well-known organic solvents of the type commonly employed in liquid detergent compositions such as ethanol, isopropanol, etc.

The germicidal detergent composition according to this invention may also contain various neutral and acid builders of inorganic and organic types which are well known in the detergent art. These builders include alkali metal and alkaline earth inorganic builders such as sodium sulfate, magnesium sulfate, sodium chloride, and the like. Acidic inorganic builders may be illustrated by sodium hydrogen phosphates, acid triphosphates, etc. Salts of sulfamic acid and of simple aromatic sulfonic acids such as benzene and naphthalene sulfonic acids may also be employed.

Although it is believed that the nature of the germicidal detergent composition of this invention will be clearly understood from the foregoing descriptions, the following examples are offered as additional illustrations. Unless otherwise specified, the proportions given are on a weight basis.

Example 1.—94.6 grams of an approximately 50% by weight aqueous solution of dodecylbenzyl diethylethanol quaternary ammonium chloride was combined with 5.4 grams of iodine. The mixture was heated to a temperature of from about 120 to about 150° F. for a period of about 20 minutes, while stirring continuously. The quaternary-iodine complex thus obtained had the following analysis:

	Per cent
Dodecylbenzyl diethylethanol quaternary ammonium chloride	46.3
Iodine	5.1
Water	48.6

The iodine contained in the complex reacted with sodium thiosulfate, indicating that it was available as elemental iodine rather than being chemically substituted in the quaternary ammonium salt molecule. A negative starch color test in aqueous medium was obtained on the complex product, indicating that it was substantially free of unbound iodine.

16.2 grams of the dodecylbenzyl diethylethanol quaternary ammonium chloride-iodine complex prepared above were mixed with 96.5 grams of a detergent composition comprising 51.8% of dodecylbenzene sodium sulfonate, 32.6% isopropanol and 15.6% water. The resulting mixture possessed the following analysis:

	Per cent
Dodecylbenzyl diethylethanol quaternary ammonium chloride-iodine	8.0
Dodecylbenzene sodium sulfonate	47.8
Isopropanol	29.8
Water	14.4

Upon testing, the above composition was found to possess a high degree of germicidal activity and excellent detergent properties.

Example 2.—750 grams of a dried anionic detergent comprising 40% dodecylbenzene sodium sulfonate and 60% sodium sulfate were mixed with 1000 grams of water to form a slurry. 50 grams of dodecylbenzyl diethylethanol quaternary ammonium chloride-iodine complex containing about 10% by weight of iodine based on the quaternary were then added to the slurry with stirring. The resulting slurry was drum-dried on rollers heated by steam at 100 lbs. per sq. in. gauge pressure to give the following composition:

	Per cent
Dodecyl benzene sodium sulfonate	37.5
Dodecylbenzyl diethylethanol quaternary ammonium chloride-iodine complex	6.3
Sodium sulfate	56.2

This germicidal detergent composition in dry form was found to be highly effective as both a germicide and a detergent when tested in accordance with the procedures described below.

Example 3.—86 grams of 46.5% by weight aqueous solution of dodecylbenzyl trimethyl quaternary ammonium chloride were combined with 10 grams of iodine. The mixture was heated to a temperature of from about 120 to 150° F. for a period of about 20 minutes, while stirring continuously. The quaternary-iodine complex thus obtained had the following analysis:

	Per cent
Dodecylbenzyl trimethyl quaternary ammonium chloride	41.6
Iodine	10.4
Water	48.0

65 The iodine contained in the complex reacted with sodium triosulfate, indicating that it was available as elemental iodine, but the iodine of the complex did not give a positive starch color test.

70 4.2 grams of the dodecylbenzyl trimethyl quaternary ammonium chloride-iodine complex were mixed with 200 grams of a detergent composition comprising 45.5% of dodecylbenzene sodium sulfonate, 12.1% lauric isopropanol amide, 28.6% isopropanol, and 13.8% water. The resulting mixture possessed the following analysis:

Per cent						
Dodecylbenzyl trimethyl quaternary ammonium chloride-iodine	1.0					
Dodecylbenzene sodium sulfonate	44.5					
Lauric isopropanol amide	11.9	5				
Isopropanol	28.1					
Water	14.5					

This composition was found to possess a high degree of germicidal activity and excellent detergent properties.

In illustration of the effectiveness of the germicidal detergent composition according to the invention, various representative compositions were tested against samples of sterile water artificially inoculated with a mixed culture of *Staphylococcus aureus*, *Escherichia coli*, and *Bacillus cereus*, which are all commonly known bacteria for the testing of germicidal agents. The tests were carried out at various concentrations of organic anionic detergent and quaternary ammonium germicide-halogen complex and the decrease in number of bacteria was observed at different times.

From the tabulated results it is readily apparent that when a typical quaternary ammonium germicide such as dodecyl benzyl trimethyl ammonium chloride is mixed with a typical anionic detergent such as dodecyl benzene sodium sulfonate, the bactericidal activity of the quaternary is markedly decreased. On the other hand, when a quaternary ammonium germicide-halogen complex product is employed with the anionic detergent in accordance with the principle of this invention, a very high bactericidal activity is found. The bactericidal activity of the anionic detergent and quaternary ammonium germicide-halogen complex composition is fully as good as compositions containing anionic detergent and free iodine. As mentioned before, the anionic detergent and free iodine compositions are entirely unsatisfactory, not because of lack of germicidal activity, but, rather, because of their toxic vapors, their tendency to stain skin and textiles, and their corrosive action on equipment and human tissue.

20 The dried germicidal detergent composition prepared

¹ Bacterial culture consisting of mixture of *Staphylococcus aureus*, *Escherichia coli*, and *Bacillus cereus*.

As a further demonstration of the utility of the germicidal detergent compositions according to this invention, liquid blends of anionic detergent and quaternary-halogen complex product with foam stabilizer and solvent prepared as in Example 3 above were also tested against a mixed bacteria culture of *Staphylococcus aureus*, *Escherichia coli*, and *Bacillus cereus*, as previously described. The results of these tests are given for an illustrative liquid blend in the following table.

30 anionic detergent, dodecylbenzene sodium sulfonate, with and without an illustrative quaternary ammonium germicide-iodine complex, namely, dodecylbenzyl trimethyl quaternary ammonium chloride containing 10% iodine, were tested for dishwashing detergency and foam heights. 35 The dishwashing detergency test was carried out by actually washing dishes soiled with 15 grams of lard oil per plate in a dishwater of a given hardness while employing the detergent composition in ordinary use concentration. The

TABLE IV

¹ Bacterial Culture consisting of mixture of *Staphylococcus aureus*, *Escherichia coli*, and *Bacillus cereus*.

It is apparent from the results tabulated above that the germicidal detergent composition of the present invention may be prepared in either dry or liquid form and, further, that various amounts of other materials commonly employed in detergent compositions such as foam

75 number of plates washed and the resulting effect on the dishwater were noted. The foam height of the composition was determined according to the method of Ross & Miles published in the *Oil & Soap Journal*, vol. 18, pages 99-102 (May 1941). Table V which follows shows the results of the tests.

TABLE V
Dishwashing detergency and Ross-Miles foam heights of

The test results tabulated above demonstrate the excellent detergent properties of the germicidal detergent compositions according to this invention. The compositions in addition to being highly germicidal, possess pronounced detergent properties equal to those of the germicidally inactive anionic detergent alone.

We claim:

1. A germicidal detergent composition consisting essentially of 70 to 99.5 parts by weight of an organic anionic detergent of the group consisting of water-soluble alkali metal salts of an organic sulfuric reaction product having in its molecular structure a higher molecular alkyl radical of from 8 to 18 carbon atoms and a radical selected from the group consisting of sulfonic acid and sulfuric acid ester radicals and 0.5 to 30 parts by weight of a quaternary ammonium germicide halogen complex consisting of from about 0.01 to about 1.0 mols of physically-bound elemental iodine per mol of quaternary ammonium germicide which are determinable by thiosulfate titration, and a quaternary ammonium germicide of the group consisting of long-chain alkyl dimethyl benzyl quaternary ammonium halides, long-chain alkyl phenoxy alkoxy alkyl dimethyl benzyl quaternary ammonium halides, long-chain alkyl pyridinium halides, long-chain alkyl trimethyl quaternary ammonium halides, long-chain alkyl benzyl di-ethyl ethanol ammonium halides and long-chain alkyl benzyl trimethyl ammonium halides, said complex being substantially free of unbound halogen as demonstrated by its failure to form halogen amines when exposed to ammonia vapors.

2. A germicidal detergent composition consisting essentially of about 70 to 99.5 parts by weight of an alkali metal salt of a higher aliphatic sulfuric acid ester having from 8 to 18 carbon atoms in the alkyl radical and about 0.5 to 30 parts by weight of a quaternary ammonium germicide and iodine complex consisting of from about 0.01 to about 0.7 mols of physically-bound elemental iodine per mol of quaternary ammonium germicide which are determinable by thiosulfate titration, and a quaternary ammonium germicide of the group consisting of long-chain alkyl dimethyl benzyl quaternary ammonium halides, long-chain alkyl phenoxy alkoxy alkyl dimethyl benzyl quaternary ammonium halides, long-chain alkyl pyridinium halides, long-chain alkyl trimethyl quaternary ammonium halides, long-chain alkyl benzyl di-ethyl ethanol ammonium halides and long-chain alkyl benzyl trimethyl ammonium halides, said complex being substantially free of unbound iodine as indicated by a negative starch color test in aqueous medium.

3. A germicidal detergent composition consisting essentially of about 70 to 99.5 parts by weight of an alkali metal salt of a higher aliphatic sulfuric acid ester having from about 8 to 18 carbon atoms in the alkyl radical, from

about 0.5 to 30 parts by weight of a quaternary ammonium germicide and iodine complex consisting of from about 0.01 to 0.7 mol of physically-bound elemental iodine per mol of quaternary ammonium germicide which are determinable by thiosulfate titration, and a quaternary ammonium germicide of the group consisting of long-chain alkyl dimethyl benzyl quaternary ammonium halides, long-chain alkyl phenoxy alkoxy alkyl dimethyl benzyl quaternary ammonium halides, long-chain alkyl pyridinium halides, long-chain alkyl trimethyl quaternary ammonium halides, long-chain alkyl benzyl di-ethyl ethanol ammonium halides and long-chain alkyl benzyl trimethyl ammonium halides, said complex being substantially free of unbound iodine as indicated by a negative starch color test in aqueous medium.

4. A germicidal detergent composition consisting essentially of about 70 to 99.5 parts by weight of an alkali metal alkyl aryl sulfonate having from 8 to 18 carbon atoms in the alkyl radical thereof and from about 0.5 to about 30 parts by weight of a quaternary ammonium germicide and iodine complex consisting of from about 0.1 to 0.7 mol of physically-bound elemental iodine per mol of quaternary ammonium germicide which are determinable by thiosulfate titration, and a quaternary ammonium germicide of the group consisting of long-chain alkyl dimethyl benzyl quaternary ammonium halides, long-chain alkyl phenoxy alkoxy alkyl dimethyl benzyl quaternary ammonium halides, long-chain alkyl pyridinium halides, long-chain alkyl trimethyl quaternary ammonium halides, long-chain alkyl benzyl di-ethyl ethanol ammonium halides and long-chain alkyl benzyl trimethyl ammonium halides, said complex being substantially free of unbound iodine as indicated by a negative starch color test in aqueous medium.

5. A germicidal detergent composition consisting essentially of about 70 to 99.5 parts by weight of an alkali metal alkyl aryl sulfonate having from 8 to 18 carbon atoms in the alkyl radical thereof, from about 0.5 to about 30 parts by weight of a quaternary ammonium germicide and iodine complex consisting of from about 0.01 to 0.7 mol of physically-bound elemental iodine per mol of quaternary ammonium germicide which are determinable by thiosulfate titration, and a quaternary ammonium germicide of the group consisting of long-chain alkyl dimethyl benzyl quaternary ammonium halides, long-chain alkyl phenoxy alkoxy alkyl dimethyl benzyl quaternary ammonium halides, long-chain alkyl pyridinium halides, long-chain alkyl trimethyl quaternary ammonium halides, long-chain alkyl benzyl di-ethyl ethanol ammonium halides and long-chain alkyl benzyl trimethyl ammonium halides, said complex being substantially free of unbound iodine as indicated by a negative starch color test in aqueous medium.

ides and long-chain alkyl benzyl trimethyl ammonium halides, said complex being substantially free of unbound iodine as indicated by a negative external starch color test in aqueous medium and about 0.1 to 50 parts by weight of a fatty acid lower alkanol amide based on 100 parts by weight of the combined sulfonate and quaternary iodine complex.

6. A germicidal detergent composition consisting essentially of about 70 to 99.5 parts by weight of an alkali metal alkyl sulfate containing from 12 to 18 carbon atoms in the alkyl radical thereof, from about 0.5 to about 30 parts by weight of a quaternary ammonium germicide and iodine complex consisting of from about 0.01 to 0.7 mol of physically-bound elemental iodine per mol of quaternary ammonium germicide which are determinable by thiosulfate titration, and a quaternary ammonium germicide of the group consisting of long-chain alkyl dimethyl benzyl quaternary ammonium halides, long-chain alkyl phenoxy alkoxy alkyl dimethyl benzyl quaternary ammonium halides, long-chain alkyl pyridinium halides, long-chain alkyl trimethyl quaternary ammonium halides, long-chain alkyl benzyl di-ethyl ethanol ammonium halides and long-chain alkyl benzyl trimethyl ammonium halides, said complex being substantially free of unbound iodine as indicated by a negative external starch color test in aqueous medium and about 0.1 to 30 parts by weight of a fatty acid lower alkanol amide based on 100 parts by weight of the combined sulfate and the quaternary ammonium germicide and iodine complex.

7. A germicidal detergent composition consisting essentially of about 70 to about 99.5 parts by weight of an alkali metal alkyl benzene sulfonate having from 12 to 15 carbon atoms in the alkyl radical thereof, from about 0.5 to about 30 parts by weight of a quaternary ammonium germicide and iodine complex consisting of from about 0.1 to 0.7 mol of physically-bound elemental iodine per mol of quaternary ammonium germicide which are determinable by thiosulfate titration, and a quaternary ammonium germicide of the group consisting of long-chain alkyl dimethyl benzyl quaternary ammonium halides, long-chain alkyl phenoxy alkoxy alkyl dimethyl benzyl quaternary ammonium halides, long-chain alkyl pyridinium halides, long-chain alkyl trimethyl quaternary ammonium halides, long-chain alkyl benzyl di-ethyl ethanol ammonium halides and long-chain alkyl benzyl trimethyl ammonium halides, said complex being substantially free of unbound iodine as indicated by a negative external starch color test in aqueous medium and about 0.1 to 50 parts by weight of a fatty acid lower alkanol amide based on 100 parts by weight of the combined sulfonate and the quaternary ammonium germicide and iodine complex.

8. A germicidal detergent composition consisting essentially of about 95 to about 99 parts by weight of an alkali metal alkyl sulfate containing from 12 to 18 carbon atoms in the alkyl radical thereof, from about 1 to about 5 parts by weight of a complex consisting of iodine and dodecyl benzyl trimethyl quaternary ammonium chloride containing about 10% by weight of physically-bound iodine in elemental form based on the dodecyl benzyl trimethyl quaternary ammonium chloride present which is determinable by thiosulfate titration, said complex being free of unbound iodine as indicated by a negative external starch color test in aqueous medium and about 10 to 30 parts by weight of lauric isopropanol amide based on 100 parts by weight of the combined sulfonate and the iodine and dodecyl benzyl trimethyl quaternary ammonium chloride complex.

9. A germicidal detergent composition consisting essentially of about 95 to about 99 parts by weight of an alkali metal alkyl benzene sulfonate having from 12 to 15 carbon atoms in the alkyl radical thereof, from about 1 to about 5 parts by weight of a complex consisting of iodine and dodecyl benzyl trimethyl quaternary ammonium chloride containing about 10% by weight of physically-bound iodine in elemental form based on the

dodecyl benzyl trimethyl quaternary ammonium chloride present which is determinable by thiosulfate titration, said complex being free of unbound iodine as indicated by a negative external starch color test in aqueous medium and about 10 to 30 parts by weight of lauric isopropanol amide based on 100 parts by weight of the combined sulfonate and the iodine and dodecyl benzyl trimethyl quaternary ammonium chloride complex.

10. A germicidal detergent composition consisting essentially of from about 95 to about 99 parts by weight of an alkali metal alkyl benzene sulfonate having from 12 to 15 carbon atoms in the alkyl radical thereof, from about 1 to about 5 parts by weight of a complex consisting of iodine and dodecyl benzyl dimethyl benzyl quaternary ammonium chloride containing about 10% by weight of physically-bound iodine in elemental form based on the dodecyl benzyl dimethyl quaternary ammonium chloride which is determinable by thiosulfate titration, said complex being substantially free of unbound iodine as indicated by a negative external starch color test in aqueous medium and about 10 to 30 parts by weight of lauric isopropanol amide based on 100 parts by weight of the combined sulfonate and the iodine and dodecyl benzyl dimethyl benzyl quaternary ammonium chloride complex.

11. A germicidal detergent composition consisting essentially of from about 95 to about 99 parts by weight of an alkali metal alkyl sulfate containing from 12 to 18 carbon atoms in the alkyl group, from about 1 to about 5 parts by weight of a complex consisting of iodine and dodecyl benzyl di-ethyl ethanol quaternary ammonium chloride containing about 20% by weight of physically-bound iodine in elemental form based on the dodecyl benzyl di-ethyl ethanol quaternary ammonium chloride present which is determinable by thiosulfate titration, said complex being substantially free of unbound iodine as indicated by a negative external starch color test in aqueous medium and about 10 to 30 parts by weight of lauric isopropanol amide based on 100 parts by weight of the combined sulfate and the iodine and dodecyl benzyl di-ethyl ethanol quaternary ammonium chloride complex.

12. A germicidal detergent composition consisting essentially of from about 95 to about 99 parts by weight of an alkali metal alkyl benzene sulfonate having from 12 to 15 carbon atoms in the alkyl radical thereof, from about 1 to about 5 parts by weight of a complex consisting of iodine and dodecyl benzyl di-ethyl ethanol quaternary ammonium chloride containing about 20% by weight of physically-bound iodine in elemental form based on the dodecyl benzyl di-ethyl ethanol quaternary ammonium chloride present which is determinable by thiosulfate titration, said complex being free of unbound iodine as indicated by a negative starch color test in aqueous medium and about 10 to 30 parts by weight of lauric isopropanol amide based on 100 parts by weight of the combined sulfonate and the iodine and dodecyl benzyl di-ethyl ethanol quaternary ammonium chloride complex.

13. A liquid germicidal detergent composition consisting essentially of about 45% by weight of sodium lauryl sulfate, about 1% by weight of dodecyl benzyl di-ethyl ethanol quaternary ammonium chloride containing about 20% by weight of physically-bound iodine in elemental form based on the dodecyl benzyl di-ethyl ethanol quaternary ammonium chloride which is determinable by thiosulfate titration, said quaternary and iodine complex being substantially free of unbound iodine as indicated by a negative starch color test in aqueous medium, about 12% by weight of lauric isopropanol amide, about 26% by weight of ethanol and about 16% by weight of water.

14. A liquid germicidal detergent composition consisting essentially of about 45% by weight of sodium dodecyl benzene sulfonate, about 1% by weight of dodecyl benzyl di-ethyl ethanol quaternary ammonium chloride containing about 20% by weight of physically-bound iodine in elemental form based on the dodecyl benzyl di-ethyl ethanol quaternary ammonium chloride which is deter-

15

minable by thiosulfate titration, said quaternary and iodine complex being substantially free of unbound iodine as indicated by a negative starch color test in aqueous medium, about 12% by weight of lauric isopropanol amide, about 26% by weight of ethanol and about 16% by weight of water.

15. A liquid germicidal detergent composition consisting essentially of about 45% by weight of sodium dodecyl benzene sulfonate, about 1% by weight of dodecyl benzyl trimethyl quaternary ammonium chloride containing about 20% by weight of physically-bound iodine in elemental form based on the dodecyl benzyl trimethyl quaternary ammonium chloride which is determinable by thiosulfate titration, said quaternary and iodine complex being substantially free of unbound iodine as indicated by a negative starch color test in aqueous medium, about 12% by weight of lauric isopropanol amide, about 28% by weight of isopropanol, and about 14% by weight of water.

16

5 16. A dry germicidal detergent composition consisting essentially of about 38% by weight of sodium dodecyl benzene sulfonate, about 6% by weight of dodecyl benzyl diethyl ethanol quaternary ammonium chloride containing about 10% by weight of physically-bound iodine in elemental form based on the dodecyl benzyl diethyl ethanol quaternary ammonium chloride which is determinable by thiosulfate titration, said quaternary and iodine complex being substantially free of unbound iodine as indicated by a negative starch color test in aqueous medium and about 56% by weight of sodium sulfate.
